VAPORIZER FOR INTERNAL-COMBUSTION ENGINES.

1,110,897.

Specification of Letters Patent. Patented Sept. 15, 1914.

Application filed July 2, 1911. Serial No. 636,717.

To all whom it may concern:

Be it known that we, CHARLES EDWARD LUCKE and WILLIAM EVERETT VER PLANCK, citizens of the United States, residing in the city of New York, county of New York, and State of New York, and Schenectady, county of Schenectady, and State of New York, respectively, have invented certain new and useful Improvements in Vaporizers for Internal-Combustion Engines, of which the following is a specification.

Our invention relates to vaporizers of the kind suitable for vaporizing the heavier liquid fuels, such as crude petroleum, kerosene or other distillates, and alcohol, preparatory to using their vapors as the combustible element in explosive mixtures for driving internal combustion engines; its object being to provide a mechanism that will successfully vaporize such oils by means of the heat derived from the exhaust gases delivered from the power cylinder without such decomposition of these oils as would leave residues, and in such a manner as to maintain a constant supply of vapor at constant pressure, available at all times for the use of the engine, and in such quantities as the engine may require to carry its load without change of pressure or hand adjustment; and further to properly mix the vapor produced with sufficient air to render the mixture explosive and to maintain the proportions of air to vapor substantially constant, so that its combustion may be complete without undue excess of air; and further to regulate the amount of such explosive mixture to the combustion chamber of the engine together with some water spray in quantities suitably regulated to control the rapidity and violence of the explosion without preventing it. The mechanism by which we attain these objects makes it possible to operate internal combustion engines with these heavy liquid fuels in a regular and reliable manner without the accumulation of soot or liquid residue in the cylinder, with a clean exhaust at a maximum of power for a given displacement and at high efficiency in the consumption of the fuel. The mechanism which we use is designed to carry out certain physical processes, some of which are commonly understood and others of which we have dis-

covered, and it must be understood that the form of the mechanism may be considerably varied in the carrying out of these processes from that shown in the accompanying drawings and described in the specification below without departing from our invention. That particular process which we have discovered, and which is embodied in the mechanism here described and associated with other well-known principles, is the following:

When heat is applied to a liquid fuel its temperature will rise and it will boil. If the application of heat be further applied, its vapor will decompose, generally with the formation of lamp black or free carbon. To prevent decomposition, therefore, the application of heat must be such as to prevent superheating of the vapor which precedes and accompanies decomposition. Even if, however, the application of heat be confined to a body of liquid or to surfaces that are constantly wet with liquid, there will be a residue left in that liquid due to the fact that most of the liquid fuels are complex mixtures of materials having different boiling points. There would, therefore, be a tendency for the vapor of the lighter constituent to boil away before the heavier and leave a residue. We have discovered that when the boiling takes place in a mass of liquid constantly replenished and substantially constant in amount, the vapor distilled off will have the same composition and characteristics when liquefied as the original fuel, and that, therefore, no decomposition takes place in the liquid when there is present a substantially constant liquid body, the application of heat to which is confined to the wetted surfaces. The reason for this decomposition under these circumstances is found in the following physical explanation: It is well-known that liquids may evaporate at temperatures below their boiling points, so that if a heavy hydrocarbon oil be mixed with a lighter and heated, the vapor of the liquid escaping at its boiling point will carry off some of the vapor of the heavy below its representative boiling point, provided the former is bubbling through a body of liquid containing the latter, or, briefly, provided there is a body of liquid through which the bubbles of low boiling point vapor may pass.

Thus, some of the heavy liquid becomes vaporized at temperatures below its boiling point.

In a complex mixture containing many constituents of different boiling points, such, for example, as kerosene, we have discovered that the boiling point will continuously rise from the commencement of heating, and if the body of liquid be kept constantly replenished, will fix itself automatically at some point between the boiling points of the heaviest and lightest constituents, at which the quantity of vapor produced at or above their boiling points will be sufficient to carry off in this way the vapor of all the other heavier constituents below their respective boiling points. Thus will the mixture known by some trade name, as kerosene, for example, be completely vaporized without residue, provided the heat be applied to the wetted surfaces containing a body of liquid constantly replenished. In applying this principle to the vaporizer of an internal combustion engine it is found that the quantity of heat in the exhaust gases is many times that sufficient to accomplish the vaporization, and that the temperature of these exhaust gases is amply high for the purpose. It is desirable that the vapor exhaust at constant atmospheric pressure in order that the making of mixture of constant proportions of the vapor with atmospheric air may be accomplished by two set orifices, through one of which the vapor is drawn, and through the other of which air is drawn by the suction of the engine. The constancy of the proportions demands for such set orifices a constancy of pressure of vapor at atmospheric value because the air itself exists under that condition. For this reason we carry out our boiling processes for producing the vapor at atmospheric pressure by having the boiler constantly in communication with the air by a sufficiently wide orifice, as the amount of heat in the exhaust gases will at all times be more than sufficient to produce the vapor needed for combustion, and as the excess is greater at some times than others, especially during change from full load to no load, we provide a condensing chamber on the top of the vaporizer by extending the surfaces surrounding the orifice that maintains constant communication between the boiler and the air, and in order that these surfaces shall not be too extensive, cool them with water, but it must be understood that this water is not essential to the processes. Our vaporizer, therefore, consists of a boiler, to which is constantly supplied liquid fuel, and which is heated on its wetted surfaces by the exhaust gases. The boiler is closed except for a passage leading from its top to the open air, of large capacity. This passage is extended sufficiently to condense all excess vapor, the

condensed liquid running back into the boiler through the same passageway through which it originally escaped. To this boiler, at a point above the liquid level, is attached an orifice carrying a needle valve to permit the engine to suck an adjustable amount of vapor from the boiler into a mixing chamber carrying likewise an air orifice and damper, and similarly a water orifice and needle valve.

Referring to the drawings illustrating one form of this apparatus—Figure 1 represents a side elevation of part of an engine cylinder having our improved vaporizer attached thereto; Fig. 2 is an end elevation of the engine cylinder and a cross section of the vaporizing attachment; Fig. 3 is a top view of a base plate detached from the vaporizer, showing the exhaust passage from the engine, and beside it an opening for the admission of a torch to supply initial heat; Fig. 4 is a top view of the vaporizer, partly in section, along the line A—B of Fig. 2; Fig. 5 is a cross section along the line B—C of Fig. 2; Fig. 6 is a vertical section of a constant level cup for supplying liquid fuel to the vaporizer; Fig. 7 represents a side elevation of part of Fig. 4; and Fig. 8 is a vertical section of Fig. 5 along the line C—D.

The same reference characters designate like parts throughout the several views.

1 represents the power cylinder of an internal combustion engine; 2 a cylinder head having an intake valve 3 and exhaust valve 4 controlling the admission and exhaust ports formed therein; 5 a valve operating lever; 6 a passage leading from the mixing chamber 7 to the admission port, and 8 a passage for the exhaust gases leading from the exhaust port. The intake port is provided with a flange 9 at its upper end whereby it is secured to the lower end of the mixing chamber 7.

10 represents the vaporizer, including a base plate 11 secured to the flange 12 at the upper end of the exhaust port 8, and provided with a central opening 13 therein that communicates with the exhaust port, and an additional passageway 14 terminating in a downward extending cylindrical portion 115 provided with a plug 16.

17 represents an open space into which the exhaust gases flow from the orifice 13, causing them to remain in contact with the bottom 18 of the vaporizer before they escape 120 through openings 19 to an annular chamber 20, finally reaching the exhaust pipe connection 21 and escaping thence to the atmosphere.

22 represents a cylindrical boiler provided 125 with inner and outer walls 23 and 24, respectively, spaced apart in a manner forming the intervening annular chamber 20, through which the exhaust gases circulate, and containing likewise the raised bottom 130

18, provided at its upper and lower surfaces with heat radiating ribs 25. The bottom of the boiler is directly above the passage 13 through which the hot exhaust gases escape 5 from the exhaust port, and its inclosing wall projects below the bottom and is secured to the base plate 11. 27 represents a common form of constant level feed cup communicating with the boiler by means of pipe 28, the cup being supplied with liquid through inlet pipe 29 opening into its bottom portion, and which may be connected to a source of supply. The excess of liquid fuel supplied escapes through an overflow 10 pipe 20 that conducts it to the supply tank in any preferred manner. The constant level feed cup is adapted to maintain a predetermined quantity of liquid fuel in the boiler by means of the constantly open communicating 15 pipe.

20 31 represents a cover for the boiler, and 32 is a condensing chamber arranged above the boiler and communicating with the atmosphere by means of openings 32¹ near the 25 upper end of its side walls, the chamber being spaced from the boiler cover and attached to it by means of a pipe 33. This condensing chamber or free boiler vent includes an outer cylindrical vessel 34, having 30 a flange 35 on its upper end, to which is attached a cover plate 36.

35 37 represents a cylindrical vessel arranged within the outer one and having an intervening space 38 between the two, and having 40 interior walls 39 to give a large surface of contact between the water in the chamber 40 and the vapor in chamber 41.

40 38¹ represents a cylindrical baffle open at its upper end and received by vessel 37, its 45 lower end being provided with a flange 39¹ whereby it is secured to the bottom of the condensing chamber, and 40¹ represents 50 openings through the lower ends of the walls of the baffle for the egress of condensed vapor. The inner vessel 37 is attached to the condenser cover which, in turn, carries a pipe connection 42 to supply water to the vessel, and another pipe 43 for its escape, the 55 water being supplied to this chamber from the jacket of the engine cylinder or other source of supply. It must be understood that this condenser cover may be entirely removed and no water supplied at all, condensation taking place by contact with the air, water being used as here indicated merely to sufficiently reduce the amount of surface needed.

55 The mixing chamber 7 includes a vertically arranged cylindrical passageway 44, 60 secured to the side of the boiler and having a vapor admission valve 45 adapted to control a port 46 communicating with the upper part of the boiler. The wall of the mixing chamber includes a part of the outer 65 wall of chamber 20, and the two chambers

receive heat from the exhaust gases that pass through openings 19 leading from the bottom of the boiler to the annular passageway 20 surrounding it. The upper end of the mixing chamber communicates with the atmosphere by means of a pipe 47, and 48 represents a common form of butterfly valve or damper located in the mixing chamber between the vapor inlet port and the air. This damper is adapted to regulate the supply of air drawn into the mixing chamber, and 49 represents a similar valve located between the vapor inlet valve and the engine inlet passage, adapted to control the supply of gasified mixture passing to the engine 70 from the mixing chamber. A bell crank lever 50 is secured to the stem of valve 49, and one arm of this lever may be attached to the governor mechanism of the engine by means of the rod 51, the other arm being 75 connected to a lever 52 secured to the stem of valve 48 by means of a link 53. These two dampers 48 and 49 may be adjusted one with respect to the other, and once adjusted may be permanently connected, maintaining a 80 constant proportion of vapor to air for all positions of the governor rod 51, in accordance with the load demand.

85 For the purpose of supplying water to the explosive mixture there is provided a port 54 in the wall of the mixing chamber, having an adjusting valve 55 to regulate the flow of water from the source of supply to the mixing chamber in a manner similar to that for regulating the flow of vapor to the mixing chamber. Water is supplied to the port 54 by a pipe 56 communicating with a constant level feed cup 57 which, in turn, is supplied with water from the jacket or other source through a feed pipe 58, the excess of 90 supply over demand escaping to the overflow pipe 59. The overflow edge of the overflow pipe 59 determines the height of water in this cup, and is to be placed sufficiently below the water inlet pipe 56 to prevent any 95 water entering the mixing chamber at no load, at which time the vacuum in the mixing chamber is a minimum and insufficient to lift the water to the port 54.

100 When the apparatus is in operation oil is 115 supplied to the constant level cup from a source of supply by means of a pump or means equivalent thereto. From this cup it flows into the boiler until the level in the boiler has become substantially equal to 120 that in the cup, which level will be constantly maintained, thus introducing a body of liquid in the boiler, against the bottom of which the hot exhaust gases come in contact. Before starting the engine the boiler 125 is heated by means of a torch supplied to the pipe connected to the opening 14, the plug having been removed for that purpose. This application of heat by means of a torch is to be continued until the liquid in the 130

boiler has reached a boiling condition and vapor is rising to the condenser, where it is condensed and returned. At this time the vapor valve 45 will be opened a suitable amount and the engine started. As soon as the engine is in operation the heat from the exhaust gases as they flow under the boiler and around its sides is sufficient to rapidly vaporize the oil and maintain not only a sufficient supply of vapor for the engine, but in addition enough to maintain constantly a condition of condensation in the condenser with return of liquid. At this time the plug is to be reinserted in the passage, thus closing it and directing the exhaust up the exhaust passage.

What we claim as our invention, and desire to secure by Letters Patent, is:

1. A vaporizer for internal combustion engines including, in combination, a boiler adapted to contain a limited amount of liquid fuel, means for maintaining a predetermined level of liquid in said boiler, said boiler having a surrounding heat receiving chamber open to the atmosphere, an engine cylinder provided with intake and exhaust ports, said heat receiving chamber communicating with said exhaust port, a vapor condenser arranged above said boiler and having free communication with the upper level thereof and with the atmosphere, and a separate mixing chamber having a valve controlled port communicating directly with said boiler and with said cylinder intake port.

2. A vaporizer for internal combustion engines including, in combination, a boiler adapted to contain a limited amount of liquid fuel, means for maintaining a predetermined level of fuel in said boiler, said boiler having a raised bottom and a surrounding heat receiving chamber extending below said bottom and above the level of liquid in said boiler, an engine cylinder provided with intake and exhaust ports, said heat receiving chamber communicating with said exhaust port, a vapor condenser arranged above said boiler, and an open pipe connection between the bottom of said condenser and the upper part of said boiler, the upper part of said condenser being in free communication with the atmosphere, and a mixing chamber attached to the side of said boiler and having a valve controlled port communicating with the upper level thereof and with said intake port.

3. A vaporizer for internal combustion engines including, in combination, a boiler adapted to contain a limited amount of liquid fuel, means for maintaining a predetermined level of liquid in said boiler, a source of heat supply communicating with said boiler, a vapor condenser having an opening in its bottom in free communication with the upper part of said boiler and other

openings in its walls at its upper level in free communication with the atmosphere, a water vessel arranged within said condenser, the bottom of said vessel having vertical interior walls forming vertical chambers that are open at their lower ends, a baffle secured to the bottom of said condenser, surrounding the opening therein that communicates with said boiler and projecting into the chamber in said water vessel, an engine cylinder, and a mixing chamber communicating therewith and with said boiler.

4. A vaporizer for internal combustion engines including, in combination, an engine cylinder having intake and exhaust passages communicating therewith, a boiler mounted upon said cylinder and adapted to contain a limited amount of liquid fuel, means for maintaining a predetermined level of liquid in said boiler, said boiler having a surrounding chamber communicating with said exhaust passage, a vapor condenser arranged above said boiler and having an open pipe connection therewith, said condenser having free communication at its upper level with the atmosphere, a water vessel arranged within said condenser and having vertical interior walls forming chambers that are open at their lower ends, a cylindrical baffle secured to the bottom of said condenser surrounding said open pipe connection, having its open upper end extending into the chamber formed in the bottom of said water vessel, said baffle having openings near the lower ends of its walls permitting the condensed vapor to flow back to the boiler, a mixing chamber connected with one side of said boiler and communicating with said engine cylinder, and a valve controlled port communicating with said mixing chamber and the upper level of said boiler.

5. A vaporizer for internal combustion engines including, in combination, an engine cylinder having intake and exhaust passages, a boiler, means for maintaining a predetermined level of liquid fuel in said boiler, a base plate secured to the lower end of said boiler, there being an intervening space between the bottom of said boiler and said plate, an opening in said plate communicating with said exhaust passage, an annular chamber surrounding said boiler and communicating with the space below the bottom thereof and with the atmosphere, a mixing chamber connected with said boiler, the inner wall of said mixing chamber forming part of the outer wall of said annular chamber whereby the exhaust gases come in direct contact with the inner wall of said mixing chamber, a valve controlled port communicating with said mixing chamber and said boiler, and a vapor condenser having free communication with the upper part of said boiler and the atmosphere.

6. A vaporizer for internal combustion engines including, in combination, an engine cylinder including a cylinder head having valve controlled intake and exhaust ports 5 therein, mixture and exhaust passages leading upward from said ports and terminating in flanged heads, a base plate secured to the head of said exhaust passage and having an opening therein communicating with 10 said passage, a boiler secured to said base plate, said boiler having double walls projecting above and below the bottom thereof, forming a chamber surrounding said boiler, a passage leading from said chamber to the 15 atmosphere, openings in the inner wall of said chamber and communicating with the space between the bottom of said boiler and said base plate, a constant level cup mechanism communicating with the source of liquid 20 fuel supply and said boiler in a manner to maintain a constant level of liquid therein, a cover secured to said boiler and having an opening therein in free communication with the bottom of a vapor condensing chamber 25 arranged above said boiler, said condensing chamber having its upper level in free communication with the atmosphere, a water vessel arranged within said condensing chamber, a vertically arranged mixing 30 chamber secured to the flanged head of said
- intake passage and to the side of said boiler, and a valve controlled port communicating with the upper level of said boiler and said mixing chamber.
7. In a vaporizer for internal combustion engines, the combination of a boiler, a liquid fuel supply means adapted to maintain a predetermined level of liquid fuel in said boiler, a condenser mounted on said boiler, a source of heat supply for said boiler, and 40 means whereby the liquid fuel in said boiler may be vaporized at all times at atmospheric pressure.
8. In a vaporizer for internal combustion engines, the combination of a boiler in communication at all times with the atmosphere, liquid fuel supply means adapted to maintain a predetermined level of liquid fuel in said boiler, a condenser mounted on said boiler and a source of heat supply for said 50 boiler.
